UNITED STATES PATENT OFFICE.

CHRISTIAN H. C. KOCH, OF CHICAGO, ILLINOIS, ASSIGNOR TO CHICAGO DISTRIBUTING AND TRADING COMPANY, OF CHICAGO, ILLINOIS, A CORPORATION OF ILLINOIS.

PROCESS OF TREATING LIQUORS BY ELECTRICITY.

No. 859,178.

Specification of Letters Patent.

Patented July 2, 1907.

Application filed September 5, 1902. Serial No. 122,148.

To all whom it may concern:

Be it known that I, CHRISTIAN H. C. KOCH, a citizen of the United States, residing at Chicago, in the county of Cook and State of Illinois, have invented a certain 5 new and useful Improvement in Processes for Treating Liquors by Electricity, of which the following is a specification.

My invention relates to a process for treating liquors by electricity and has for its object to provide a new 10 method and apparatus for this purpose.

My invention is illustrated in the accompanying drawings, wherein

Figure 1 shows a simple apparatus by means of which my invention may be carried out; Fig. 2 is a sectional 15 view therethrough; Fig. 3 is an end view.

Like letters represent like parts throughout all of the figures.

My present invention relates particularly to the treating of alcoholic beverages or liquors, and has for 20 its object, among other things, to make the liquor better and to secure for it the results which, under ordinary conditions it is necessary to secure by age, which necessitates storing the liquor for a comparatively long period after its manufacture and before it can be 25 placed upon the market.

By means of my invention I am able to secure results in a very short period of time, which, without my invention would require storing the material for years.

30 My invention is applicable to a great variety of materials and it may be carried out in various ways.

As shown in the drawings, I have illustrated a barrel A, which may be of any material, such, for example, as the ordinary wooden barrel in which such liquors as 35 whisky and the like are placed. In such cases, for example, I provide at each end of the barrel a conducting plate B, which is placed on the end or head of the barrel and attached thereto in any desired manner, as, for example, by means of screws or the like, so that 40 it can be readily attached and removed. Each plate is provided with suitable means for connecting it to a conductor, as for example, by means of the binding bolts or screws B¹. These conductors B² and B³ are connected with a source of electric supply C, which 45 may be any suitable source, such as a dynamo, or the mains of any suitable electric circuit or the like. I prefer to use a high voltage. I have found that the ordinary street car voltage gives excellent results. The current used in street car systems is generally in 50 the neighborhood of 500 volts. I have also used a 220 volt current. It is of course evident that any other suitable voltage might be used. When the plates are in position on the heads of the barrel the current is turned on and the apparatus is left in this

condition for the proper length of time. The length 55 of time will, of course, depend upon the conditions presented, such as the voltage of the electric current, the size and material of the receptacle, etc. This period of time may, of course, be varied as desired, and may be, for example, a portion of a day, or one or more 60 days. When the current has been on a sufficient length of time to secure the desired results, the process is stopped and the material is then ready for use. With such material, for example, as whisky, I have found that when new whisky is treated in this manner 65 the roughness is taken off and it is made mild and of a good taste, although the strength is not changed, the mellowness of age being produced in a very short time.

When the construction as shown in the drawing is 70 used, I may interpose between the plates B and the heads of the barrel a thin piece of material, such as a damp cloth. The plates B are preferably made of a considerable area so as to spread out the current and cause it to pass through substantially the entire body 75 of the liquor. It is of course evident that when a wooden barrel is used, the liquor passes, for example, into the heads of the barrel, and is thus utilized in assisting in obtaining the proper current relations. The heads of the barrel, when made of wood, are more or 80 less saturated with liquor and when the damp cloth is used the outer face becomes wet or dampened. I thus have a non-metallic piece having its pores filled with liquor and I have found that this is sufficient to conduct the current, and yet there are no corrosive electrodes or electrical conductors exposed to the liquor inside of the receptacle, and hence this liquor remains 85 untarnished. If, for example, a metallic electric conductor such as copper or iron is exposed on the inner face of the receptacle, electrolytic action takes place 90 and the liquor is destroyed. This must be prevented and with my device is prevented. The metallic plates B are not in contact, therefore, with the liquor in the body of the receptacle. There must be interposed between the parts to which the circuit is connected, a 95 material forming part of the receptacle, which is a poorer conductor of electricity than the liquor itself, so that the current must come into intimate contact with the liquor itself so as to exert the proper influence thereon. The end pieces, for example, might be made 100 of different material, but under no conditions must corrosive material such as iron or copper be used in contact with the liquor.

I have described my process in detail and a particular apparatus for carrying it into effect, but it is of 105 course evident that the apparatus may be varied in many particulars, and I therefore do not limit myself to the particular construction shown.

It will be noted that by means of my invention I treat the liquor in the original package, that is the original casks or barrels in which the liquor is placed and shipped by the manufacturer, and that I treat the liquor without inserting anything into the barrel or in any manner changing the barrel.

I claim:

1. The process of treating liquors which consists in confining the liquor in a non-metallic receptacle which is a 10 poorer conductor of electricity than the liquor, the interior of the receptacle free from any conducting material so that the liquor makes contact only with the non-conducting material, then connecting two points of this receptacle with the source of electric supply so that there is 15 no metallic contact with the liquor within the receptacle and permitting the current to flow from one to the other through said liquor.

2. The process of treating liquors which consists, in applying to the cask or barrel in which the liquor is shipped 20 two electrodes, one at each end thereof, and then passing an electric current through said ends and through the said liquor without having anything other than the barrel or cask in contact with the liquor.

3. The process of aging liquors which consists in confining the liquor in a receptacle with its inner surface in 25 contact with the liquor composed entirely of non-metallic material, then connecting two separated exterior points of the receptacle in an electric circuit without allowing said liquor to come into contact with any metallic electrode,

and causing the current to be spread out as it enters the liquor so as to pass through the body of the liquor.

4. The process of treating liquors which consists in confining the liquor in a wooden receptacle, the complete interior surface of which is wood so that nothing but the wood comes into contact with the liquor, then applying electrodes at opposite points on the exterior of said receptacle, then connecting said electrodes in an electric circuit through which a current is passed and transmitting the current to the liquor in the receptacle through the wood which is in contact with the liquor, whereby the transmission of the current to the liquor is directly from the wood.

5. The process of treating liquors which consists in connecting the ends of the original receptacle in which the liquor is kept in an electric current and forcing the current through said ends and said liquor for a predetermined 40 length of time, without bringing anything other than the original receptacle into contact with the liquor so as to treat the liquor in the said original receptacle.

6. The process of treating liquors which consists in confining the liquor in a wooden receptacle and applying metallic electrodes to the exterior of the ends of said receptacle, and interposing between said metallic electrodes and said ends a sheet of moisture holding material, and applying an electric current to said electrodes and forcing such current through said ends and said liquor.
